(57) **CLAIM**

The ornamental design for an automobile front bumper, as shown and described.

DESCRIPTION

FIG. 1 is perspective view from the right side of an automobile front bumper showing my new design;

FIG. 2 is front elevation view; and,

FIG. 3 is a side elevation view.

The rear view of the surface that faces the automobile when installed is omitted and is not part of the claimed design.

1 Claim, 2 Drawing Sheets

FIG. 1

FIG. 2

FIG. 3
